ELECTROMECHANICAL VIBRATORY
SYSTEM AND APPARATUS

Carl Fichandler, New York, N. Y.

Application October 5, 1931, Serial No. 567,122

5 Claims. (Cl. 250—36)

The present invention relates to the production of mechanical and electrical vibrations or oscillations and to the resultant of interacting mechanical and electrical vibrations or oscillations.

5 It is well known that oscillations of mechanical vibrators can be produced and maintained by electrical excitation. Perhaps the best known example is the interrupter used in bells, buzzers and the like. For the production of constant frequency vibration the interrupter is not well suited, because the variable mechanical load imposed upon the vibrator by the movement of the contact arm results in vibrations of varying frequency and excessive harmonic content.

10 One object of the present invention, therefore, is to provide a method and means for producing mechanical and electrical vibrations or oscillations of constant frequency and of undistorted wave form. According to this invention an oscillating electrical and mechanical vibration is produced under the control of a mechanical and/or electrical resonator such as a reed, tuning fork, piezo-electric crystal, and the like.

15 A refinement of the interrupter method involves the excitation of a tuning fork by current variations produced by the pressure of the fork on a microphone. The disadvantages due to the variable mechanical load, as in the interrupter method, and the initial and replacement costs of the microphone are highly objectionable.

20 Another object of the present invention is to obviate the disadvantages of the tuning fork and microphone type of oscillating vibrator.

25 The highest quality type of tuning fork oscillator which is known to the art involves the use of thermionic tubes. In this type of oscillator, the action involves electric induction to the grid circuit of an amplifier tube, the plate circuit of which feeds back energy to the vibrator. In this arrangement, the vibrator serves as a tuned coupling link in an oscillatory audion circuit. While the quality of the tuning fork and tube oscillator is high, this oscillator is comparatively complicated and bulky and involves the initial and replacement costs of the tubes.

30 A further object of this invention is to provide an oscillating vibrator, the quality of which is at least as high as that of the tuning fork and tube oscillator but which does not involve thermionic tubes or the like whereby to provide a high quality oscillating vibrator of simple construction and at low cost.

35 A further object is to provide a sharply tuned amplifier for harmonic mechanical or electrical vibrations without the use of thermionic tubes or the like.

40 A further object is to provide a simple and stable source of musical tones for sound signals, electro-musical instruments, and the like.

A still further object of the invention is generally to improve oscillating vibrators.

The invention can best be understood by reference to the following description considered in connection with the accompanying drawing, in which Figure 1 is a more or less diagrammatic view of one embodiment of the invention, and Figure 2 is a similar view of another embodiment.

45 As shown in Figure 1, there is provided an electromagnetic core 1 having poles 1a and 1b spaced to provide an air gap 1c. The coil 2 energized by direct current from the battery 3 constitutes a source of flux for producing a magnetic bias in core 1. The energization of coil 2 can be regulated by the adjustable resistance 4 and switch 5 in series with said coil 2 and with a choke coil 14 the function of which is to suppress current alternations. The coil 6 is connected in series with a source of direct current, such as battery 7, a switch 8, an output impedance 9, an adjustable resistance 10 and a vibrator coil 11, which, as shown, is positioned in the air gap 1c. Said coil 11 is rigidly attached to a vibrator, which may be an acoustical vibrator such as a tuned reed spring or the like 12 which is rigidly carried by an adjustable clamping device 13 by which the coil 11 can be adjusted to the neutral position in air gap 1c. Coil 11 is so wound that its turns intersect the magnetic flux between poles 1a and 1b approximately at right angles and that the flux exerts on the current in the coil an electrodynamic force in the direction of vibration of reed 12. It will be understood that the current flowing through coil 6 is both alternating and direct, the direct current being supplied by battery 7 and the alternating current by coil 11. The battery 3 may be dispensed with as coil 2 may be energized by battery 7 or an equivalent permanent magnetic flux may be obtained by fabricating core 1 of iron having a high magnetic retentivity characteristic. The vibrator may be used as a sound generator or as a source of electrical oscillations, the coupling impedance 9 comprising means for transferring the latter to one or more circuits (not shown).

50 Undamped oscillations can be produced by the apparatus shown in Fig. 1 when the direct current component of the flux produced by coil 6 is opposed to the flux produced by coil 2 and is less than one-half of the latter, as will appear from the following explanation. The operation of the apparatus shown in Fig. 1 depends upon interacting magnetic, electrical, and mechanical forces.

55 The flux, ϕ , in the electromagnet 1 is produced first by a constant current i flowing through the coil 2. The intensity of this current is known and determined by the E. M. F. of 3 and the resistance of 4. Fluctuations are pre-

70

100

105

110

115

120

vented by choke 14. The inductance of 2 is of the known magnitude L_2 . A second part of the flux is produced by the unknown output current i_6 flowing through the combined inductance of coils 6 and 11. We call this combined inductance, L. Since L varies slightly with the position of the vibrator coil 11, we assume that it has been measured in the neutral position of 11. Thus the flux equation becomes:

$$10 \quad \phi = \frac{L_2}{n_2} i_2 + \frac{L}{n_6} i_6 = p_2 i_2 + p i_6 \quad \text{Eq. 1}$$

Where n_2 is the effective number of turns in coil 2, and n_6 is the effective number of turns in coils 6 and 11, and

$$L_2 = p_2 \text{ and } \frac{L}{n_6} = p$$

We call the E. M. F. of battery 7, E; the total electric impedance of the output circuit 6, 8, 9, 10, 11, Z; we denote differentiation with respect to time by a prime, and find from Kirchhoff's law for the voltage in the output circuit:

$$25 \quad E - Zi_6 - (n_6 \phi)' = 0 \quad \text{Eq. 2}$$

Where $(n_6 \phi)'$ is the rate of change of induction flowing through the windings of coils 6 and 11 and producing a counter-E. M. F. according to Maxwell's law.

If H is the field strength of the magnetic flux through coil 11; if b is the total effective length of all the windings of the coil 11, measured in a direction at right angles to the flux and at right angles to the direction of vibration of coil 11 and spring 12; if y_{11} is the elongation of coil 11 in the vertical direction of vibration; if S is the effective stiffness of the vibrating system, F its effective viscous friction coefficient and M its effective mass;—then we find as condition of dynamic balance:

$$40 \quad Hbi_6 + Sy_{11} + Fy_{11}' + My_{11}'' = 0 \quad \text{Eq. 3}$$

The first term of equation 3 is the electrodynamic force, the other terms are mechanical force reactions due to stiffness, friction and inertia.

45 We eliminate ϕ and simplify Equations 2 and 3.

$$(n_6 \phi)' = L i_6 + H b y_{11} \quad \text{Eq. 4}$$

The field strength H of the approximately homogeneous field between the magnet poles is equal to the flux ϕ divided by the area of the pole faces. Hb therefore equals the flux ϕ , divided by the height of the pole face in the direction of vibration and multiplied by the number n_{11} of coil windings crossing the entire length of the pole face at right angles to the direction of vibration. Windings which cross only a part of the pole face are counted with proportionally reduced weight. The dimension of Hb is that of a flux, divided by a (known) length, which we call k . Therefore we have:

$$50 \quad Hb = \frac{\phi}{k} \quad \text{Eq. 5}$$

Or from Equation 1:

$$55 \quad Hb = \frac{p_2 i_2 + p i_6}{k} \quad \text{Eq. 6}$$

Combining 6 with 4 and 2, we find:

$$70 \quad E - Zi_6 - L i_6' - \frac{p_2 i_2 + p i_6}{k} + \frac{p_2 i_2 + p i_6}{y_{11}'} = 0 \quad \text{Eq. 7}$$

Combining 6 with 3, we find:

$$75 \quad i_6 \frac{p_2 i_2 + p i_6}{k} + Sy_{11} + Fy_{11}' + My_{11}'' = 0 \quad \text{Eq. 8}$$

In the differential Equations 7 and 8 we know all quantities but i_6 and y_{11} , which are unknown functions of time and which can be calculated from said equations, subject to boundary conditions. Since we are only concerned with proving the ability to sustain vibrations at all, we may assume that the solution will be an infinitely small vibration, superimposed to a constant deflection; and accordingly, from the electrical viewpoint, an A. C. of minute amplitude superimposed to a D. C. In this case we may neglect all harmonics of the fundamental oscillation. The solution of 7 and 8 can then be written, in symbolic form:

$$80 \quad i_6 = i_0 + i_e e^{j\omega t} \quad \text{Eq. 9a}$$

and

$$85 \quad y_{11} = y_0 + y_e e^{j\omega t} \quad \text{Eq. 9b}$$

The constant components of current and deflection are easily found. From 7 we have:

$$90 \quad E - Zi_0 = 0 \quad \text{Eq. 10}$$

or

$$95 \quad i_0 = \frac{E}{Z_0} \quad \text{Eq. 11}$$

where Z_0 is the D. C. value of the known circuit impedance Z. In the same way we find from 8:

$$100 \quad i_0 \frac{p_2 i_2 + p i_6}{k} + Sy_0 = 0 \quad \text{Eq. 12}$$

and

$$105 \quad y_0 = -\frac{i_0 (p_2 i_2 + p i_6)}{KS} \quad \text{Eq. 13}$$

Having thus determined direct current and constant spring deflection, we investigate the A. C. components of the fundamental circular frequency ω : From 7 we find: on account of $i' = i j \omega$ (Eq. 15) and $y' = y j \omega$ (Eq. 16):

$$110 \quad -Zi - Lijw - yjw \frac{p_2 i_2 + p i_6}{k} = 0 \quad \text{Eq. 14}$$

From 8 we find:

$$115 \quad i_0 \frac{p_2 i_2 + p i_6}{k} + \frac{y(S + Fjw - Mw^2)}{k} = 0 \quad \text{Eq. 17}$$

By demanding a solution of the form given by Equations 9a and 9b we have introduced the new unknown w . We therefore cannot expect to find a complete solution for i and y from 14 and 17. Such a solution would also be illogical from a physical viewpoint, because the Equations 9 signify oscillations of zero damping, that is of indifferent equilibrium. By an infinitesimal change of circuit conditions such vibrations can be made either to die out or to increase in amplitude.

What the equations can disclose, is the amplitude- and phase-relation of i to y . We therefore solve both 14 and 17 for i/y and find, from 14:

$$120 \quad \frac{i}{y} = -\frac{p_2 i_2 + p i_6}{k(L + \frac{Z}{jw})} \quad \text{Eq. 18}$$

And from 17:

$$125 \quad \frac{i}{y} = -\frac{k(S + Fjw - Mw^2)}{p_2 i_2 + 2p i_0} \quad \text{Eq. 19}$$

By equating 18 to 19 we find an equation which contains w as the only unknown quantity:

$$130 \quad k^2 (S + Fjw - Mw^2) \left(L + \frac{Z}{jw} \right) - (p_2 i_2 + p i_6) (p_2 i_2 + 2p i_0) = 0 \quad \text{Eq. 20}$$

The solution of 20 is restricted to real values of w , since we demand harmonic vibrations of

constant amplitude. We can therefore split 20 into two independent equations by equating the imaginary and the real part of 20 separately to zero. For this purpose we divide the known impedance Z of the output circuit into a resistive and a reactive component:

$$Z = R + jN \quad \text{Eq. 21}$$

10 Now we restrict our problem by specifying that we want our spring to vibrate at its own mechanical resonance frequency, which is very nearly equal to:

$$15 \quad w = \sqrt{\frac{S}{M}} \quad \text{Eq. 22}$$

20 This means that instead of trying to express the frequency by arbitrary circuit constants we utilize the known frequency for the purpose of determining circuit conditions favorable to sustained oscillations.

By substituting Equations 21 and 22 into equation 20, we find:

$$25 \quad k^2 F j w \left(L + \frac{N}{w} + \frac{R}{j w} \right) - (p_{2i2} + p'y) (p_{2i2} + 2p_{i0}) = 0 \quad \text{Eq. 23}$$

The imaginary part of 23 gives us:

$$30 \quad k^2 F j w \left(L + \frac{N}{w} \right) = 0 \quad \text{Eq. 24}$$

or

$$35 \quad N = -Lw \quad \text{Eq. 25}$$

Equation 25 means that the combined circuit impedance of 6, 7, 9, 10, 11 must be purely resistive; the external impedance must have a capacitive component which compensates for the inductance L .

40 The real part of 23 gives us:

$$45 \quad k^2 F R = (p_{2i2} + 2p_{i0}) (p_{2i2} + p_{i0}) \quad \text{Eq. 26}$$

The left side of 26 is composed of intrinsically positive quantities. Therefore the factors of the right side must be either both positive or both negative.

Further information as to the value of these factors, which represent magnetic fluxes, is obtained, when we divide Equation 26 by Equation 13, which gives us:

$$50 \quad \frac{k^2 F R}{j w} = -\frac{L}{R} \cdot \frac{(p_{2i2} + 2p_{i0})}{L_{i0}} \cdot S k \quad \text{Eq. 27}$$

In view of the relation between L and p (Equation 1) we can rearrange 27 into:

$$55 \quad \frac{k n_0 F_w}{S y_0} = -\frac{L w}{R} \left(2 + \frac{p_{2i2}}{p_{i0}} \right) \quad \text{Eq. 28}$$

60 The left side of 28 is the quotient of a friction force by stiffness force. It is therefore of the same order of magnitude as the damping factor of the spring; that is, much smaller than one.

65 The right side of 28 is the product of two factors, at least one of which will also have to be much smaller than one in order to satisfy the equation.

70 The first of these factors is the quotient of the inductive impedance of coils 6 and 11 by the effective circuit resistance. Making this factor small by an increase of external ohmic resistance would result in a very inefficient apparatus, because a generator produces a maximum output when internal and external impedances are equal. The external effective resistance can be raised

without loss in efficiency by antiresonant tuning of circuit impedances.

We conclude therefore that the absolute value of the second factor must be much smaller than one:

$$80 \quad 2 + \frac{p_{2i2}}{p_{i0}} \ll 1 \quad \text{Eq. 29}$$

Consequently, p_{2i2} is approximately equal to $-p_{i0}$. This makes the second factor on the right side of Equation 26, $p_{2i2} + p_{i0}$, negative. Therefore, the other factor must also be negative, or

$$85 \quad p_{2i2} + 2p_{i0} < 0 \quad \text{Eq. 30}$$

We find therefore, that undamped oscillations of the exact frequency

$$90 \quad \sqrt{\frac{S}{M}} \quad \text{Eq. 31}$$

can be produced when the direct current component of the flux produced by coil 6 ((p_{i0})) is opposed to the flux produced by coil 2 ((p_{2i2})) and is smaller than one-half of the latter.

The circuit conditions derived above are requirements for an undamped oscillation of infinitely small amplitude and the exact frequency of Equation 22. If we solve the circuit Equation 23 with the assumption of a fictitious damping coefficient larger than the actual one, we find circuit constants which generate a vibration with increasing amplitude. The ultimate balance in that case is achieved by second order effects, like magnetic saturation, hysteresis losses, and harmonic overtones, etc.

100 Since, by observing the requirements of Equations 25, 29, and 30, it is possible to produce oscillations of the exact frequency according to 22; it will be so much easier to generate oscillations, if the frequency requirement is eased

105 to that of vibrations at a frequency close to the natural period of the spring. We will then not be forced to adhere strictly to the impedance requirement 25. We can, instead find a more general solution of the circuit Equation 20, subject, 110 of course, to the restriction of a real value of w . It is easy to see that real solutions can always be found by making the phase angle of the electrical impedance $(L + Z/jw)$ equal and opposite to the phase angle of the mechanical impedance $(S - Mw^2 - Fjw)$.

115 Briefly described, the action of the oscillator, shown in Fig. 1, is as follows: As coil 11 is in a position of unstable balance between the mechanical force of reed stiffness and the electrodynamic force exerted by the magnetic flux on the current in coil 11, any small motion of the reed 12 produces in coil 11 an induced electromotive force which changes the current intensity in coil 6 and thereby affects the magnetic flux 120 in such a way that the motion of reed 12 is amplified into an oscillatory vibration, if the circuit constants are adjusted within the proper amplitude and phase range.

125 As shown in Figure 2, the vibrator 15, here shown as a tuning fork, is secured rigidly at one end by a clamp 16. Said fork 15 is made of iron or other magnetizable material and is part of an electro-magnet as will appear presently. An iron armature 17, secured in position by a clamp 18, has poles 17a and 17b disposed at the free ends 15a and 15b of vibrator 15 in spaced relation to provide air gaps 29 and 30 therebetween. The vibrator and magnet 15 is energized by a coil 19 which is positioned near the nodes of vibration

and is loosely associated with vibrator 15 whereby not to impede or participate in the vibrations thereof. The air gaps 29 and 30 remain substantially constant in length during the vibration. Coils 20 and 21, are mounted on pole pieces 17a and 17b. Coils 19, 20 and 21 are connected in series through a battery or other source of direct current 22, a variable resistance 23, a switch 24, and an output circuit here shown as a transformer 25. Coil 19 carries both direct current and alternating, the former being supplied from the battery 22 and the latter from the coils 20 and 21. The alternating current component in coil 19 is tuned by variable condenser 26. The apparatus as shown may be a tuned amplifier of electrical variations supplied to the input circuit which, as here shown, comprises an iron core 27 and a coil winding 28. If the circuit constants are such that the vibration losses are nearly but not completely compensated, the apparatus will serve as a sharply tuned amplifier for both mechanical and electrical oscillations of the resonant frequency of vibrator 15. For example, if a small amount of electrical energy at or near the resonance frequency is supplied to the input circuit 28, it will cause relatively violent vibrations of fork 15 and correspondingly amplified electrical output energy at the secondary of output transformer 25. Also, if the circuit constants are so adjusted in phase and amplitude relation, that the vibratory energy losses are overcompensated, any small chance vibration of fork 15 will be amplified to a saturation value and maintained thereat by the battery 22 or any other suitable power supply.

Since poles 15a and 15b of the vibrator 15 have opposite directions with respect to the flux and also to motion, coils 20 and 21 assist each other as far as the vibratory interaction is concerned. The symmetrical arrangement of coils 20 and 21 tends to reduce the harmonic content of both mechanical and electrical oscillations. Due to the inverted arrangement of poles 17a and 17b of iron core, as shown, the latter oppose each other and therefore their inductance coefficient is small. However, this inverted arrangement is not necessary.

The embodiment shown in Figure 2 differs in two important structural respects from the embodiment shown in Figure 1. Firstly, as shown in Figure 2, the coils 20 and 21 are stationary and the electro-magnet, constituted by the fork 15 and coil 19, is movable, whereas as shown in Figure 1, the coil 11 is movable and the electro-magnet, constituted by the core 1 and coil 6, is stationary. The arrangement shown in Figure 2 is preferable in this respect since it is somewhat difficult to properly secure a coil to an acoustical vibrator. Secondly, as shown in Figure 1, coil 2 is provided in order to effect the proper phase relation between vibratory motion and the fundamental frequency of electrodynamic force. This can be accomplished more economically by changing the alternating current impedance relations between the electrical circuit elements as, for example, by tuning the magnetizing coil 19 in Figure 2 by the shunt condenser 26. Thus, while I prefer the arrangement shown in Figure 2, the phase relation between vibratory motion and the fundamental frequency component of electrodynamic force may be adjusted by the magnetic biasing coil 2 or by tuning the magnetizing coil inductance 19. It will be noted that by the present invention I have eliminated the

necessity for electronic tubes or other space-discharging devices, and in this connection it will be observed that in the apparatus shown in Fig. 1 the circuit containing the winding 6 and the coil 11 being free from a space discharge path 80 has bilateral or non-directional conductivity, and in the apparatus shown in Fig. 2 the circuit containing the winding 19 and coils 20 being likewise free from a space-discharge path also has bilateral conductivity.

While I have shown two preferred embodiments of the invention, it will be obvious to those skilled in the art that changes in the parts and the arrangement thereof may be made without departing from the basic principles of the invention. For example, tuning reeds and forks may be replaced by diaphragms, air columns, crystals and the like; and the electrodynamic force exerted in the operation of the apparatus may be replaced by another electro-mechanical force, such as electromagnetic, electrostatic, piezo-electric and magnetostrictive and like forces. Also, electromagnetic induction can be replaced by electrostatic, piezo-electric and equivalent reactions. Accordingly, I do not wish to be limited to the specific embodiments shown except as may be required by the appended claims and the prior art.

Having thus described my invention, what I claim is:

1. Apparatus comprising a vibrator having a resonant frequency, an electro-magnet having an air gap, a current carrying coil secured to said vibrator disposed for movement in said air gap, an energizing winding for said electro-magnet 110 energized from said first mentioned coil, a source of direct current for said winding, and means for producing direct current flux in said magnet independent of said winding.

2. An electro-mechanical vibratory system 115 comprising a magnetizable core, a first winding and a source of electrical energy for producing flux in said core, a mechanical vibrator, and a second winding in series with said first winding and subjected to the action of said flux, said second winding being relatively movable with respect to said core under the control of said vibrator whereby electrical energy variations are induced in said second winding for controlling the flux producing action of said first winding, said two 120 windings connected to each other in said series relation by a circuit of bilateral conductivity.

3. An electro-mechanical vibratory system comprising a stationary winding, a source of electrical energy therefor, a core magnetized by said 130 winding, a mechanical vibrator, and a movable winding having an electrical connection with said stationary winding, said movable winding having electrical energy variations induced therein by movement thereof under the control of said vibrator in the field of said core for varying the 135 magnetizing action of said first mentioned winding.

4. Apparatus comprising a vibrator, an electro-magnet having an air gap, a current carrying coil secured to said vibrator disposed for movement in said air gap, an energizing winding for said electro-magnet energized from said first mentioned coil, and means for adjusting the phase relation between the vibratory motion of 140 said vibrator and the frequency component of the electro-dynamic force produced by the interaction of the current in said coil and the flux of said electro-magnet.

5. An electro-mechanical vibratory apparatus 150

comprising a first winding, a source of electrical energy, means including said winding and source of energy for producing a magnetic field, a mechanical vibrator, and a second winding in series with said first winding, said second winding being relatively movable in said magnetic field under the control of said mechanical vibrator

whereby to subject said second winding to the action of the flux of said field to induce electrical energy variations in said second winding, said two windings being connected in said series relation by a circuit of bilateral conductivity.
